UNITED STATES PATENT OFFICE.

ARTHUR E. MEIER, OF CHICAGO, ILLINOIS.

BALL.

1,263,585.

Specification of Letters Patent. Patented Apr. 23, 1918.

Application filed June 23, 1917. Serial No. 176,474.

To all whom it may concern:

- Be it known that I, ARTHUR E. MEIER, a citizen of the United States, and a resident of Chicago, in the county of Cook and State 5 of Illinois, have invented new and useful Improvements in Balls, of which the following is a description, reference being had to the accompanying drawing, which forms a part of my specification.
- 10 My invention relates to balls used for playing and more particularly to the core or center of the ball; the invention being especially applicable for use in connection with base-balls.
- 15 The invention has for its object the provision of a core or center composed of material having great resiliency; the core or center being preferably formed in the nature of a sphere upon which the remainder 20 of the ball is constructed to any desired diameter or size, by the employment of yarn or other suitable material; the nature whereof depends upon the use for which the ball is intended.
- 25 In the manufacture of base-balls, the great desideratum is to provide what is known as a "live ball," that is, a ball possessing the desired or necessary weight and at the same time having great resiliency or 30 rebound.

The object of the invention is to provide a ball wherein the center or core, whereby the resiliency imparting quality is obtained, is composed of such material as will at all 35 times retain its resiliency.

The invention is applicable for use in connection with base-balls, golf balls, indoor base-balls, and the like, wherein the core or center may be incased in a shell or covering 40 of suitable rubber, either in the nature of rubber bands or strands tightly wound upon the core, or a properly constructed rubber shell or vulcanized rubber covering, whereby the center or core is maintained 45 in its compressed condition; the degree of compression being somewhat proportional with the degree of resiliency it is desired to obtain.

The invention and its advantages will be 50 more fully comprehended from the following detailed description of the various exemplifications set forth in the accompanying drawings, wherein:

Figure 1 is a cross sectional view of a 55 base ball embodying my invention.

Fig. 2 is a partial elevation and sectional view of my improved core or center.

Fig. 3 is a cross sectional view of a modified form of my invention, showing its application to what is known as an indoor 60 base-ball.

Fig. 4 is a cross sectional view illustrating the application of my invention to a golf ball.

Fig. 5 illustrates a modified form of my 65 invention.

In the exemplification of the invention, as illustrated in Fig. 1, where the same is shown in the nature of a base-ball, 10 designates the central core, which consists of 70 sponge compressed into suitable form and preferably maintained in compressed condition by small bands or strands of rubber, indicated at 11, wound under tension upon the sponge core 10. The degree of resiliency, and therefore to a certain extent, the degree of compression of the sponge 75 may be regulated by the degree of tension under which the rubber strands or bands are wound upon the core. In this form, the 80 strands or bands of rubber are then provided with layers of soft rubber indicated at 12, which is subjected to the ordinary hardening or vulcanizing treatment induced by suitable degree of heat and pressure for 85 a predetermined period of time whereby the rubber is caused to retain the desired resiliency.

The layers of rubber 12 having been thoroughly vulcanized, the yarn, or other material, depending upon the use to which the ball is intended to be placed, is then applied to the composite core composed of the compressed sponge and rubber. Where the ball is intended to constitute a base-ball, the 90 thread or yarn is tightly wound upon this composite core, as indicated at 13 in Fig. 1; the yarn or other thread 12 being preferably wound in layers and provided with intermediate layers or coatings of adhesive 95 plastic composition, such as rubber cement, as indicated at 14 in Fig. 1. The plastic composition or cement causes the yarn or thread to be held in its firmly wound condition, and therefore also assists in maintaining the spherical contour of the various windings or layers. The yarn or thread portion of the ball may be given any number of intermediate coatings of plastic composition or cement, as indicated in Fig. 1, 110

After the ball has been formed to the desired dimensions, the whole structure is then incased in an outer cover, indicated at 15 in Fig. 1, which is preferably made of suitably cut strips of horse-hide stitched or suitably sewed together.

Where the ball is intended to constitute what is known as an indoor base-ball, after the composite core of sponge and suitable 10 strands of rubber or covering of rubber has been completed, the core is incased in suitable hair, waste or loose yarn, indicated at 16 in Fig. 3, and preferably somewhat compressed and the composite mass provided 15 with a suitable cover indicated at 17, which may be of suitable leather made of properly cut strips stitched together in the usual manner.

The composite core in a ball of this kind 20 may be identical with the core previously described and shown in Figs. 1 and 2, or may simply consist of the sponge 10 provided with a suitable number of rubber bands 11 without completely incasing the core in additional covering of vulcanized rubber 12, as 25 shown in Figs. 1 and 2.

In Fig. 4 I have shown my invention applied to a golf ball, wherein the center or core is composed of a suitable quantity of 30 sponge compressed into compact form, preferably made spherical, and then provided with rubber bands 11, which are wound thereon under tension in a manner similar to that previously described; after which 35 it is provided with a covering of gutta-percha or other suitable material, indicated at 18, of sufficient hardness so as to adapt the ball for golf.

In some instances it may be found desir- 40 able to dip the sponge in a rubber solution before applying the various windings of rubber strands.

In Fig. 5 I disclose a modified form of 45 constructing the composite core, wherein the center of sponge 10 is incased in a hollow rubber ball 19, which is properly formed or molded into shape with a small section or portion removed, as shown at 20; the section 20 being cemented or vulcanized into 50 place after the rubber shell or ball 19 has been completely filled with the sponge core. The ball 19 is provided with an opening or removed portion just large enough to permit the sponge core to be forced into the

ball under compression; the sponge being 55 firmly packed or rammed into the rubber shell or ball so as to completely fill the same while the sponge is still in its compact or compressed condition. The shell 19 having been completely filled with the compressed, 60 firmly packed sponge, the plug or section 20 is then cemented into place. This composite core may then be provided with a suitable outer covering of gutta-percha or other suitable material when it is intended to 65 provide a golf ball; or the composite center or core provided with suitable yarn or thread wound in layers, under sufficient tension, as previously described, when it is desired to construct a base-ball and the respective layers of yarn or thread preferably provided with a suitable cement, as shown in Fig. 1; the yarn or thread winding being, as before stated, provided with a suitable cover of horse-hide or other suitable 70 material.

As is apparent from the foregoing description, as well as the illustrations set forth in the drawing, great rigidity will be given to the entire ball, as a result of the 80 compressed nature of the core, and be maintained either by the tension of the winding of the encircling rubber strands, or the incasing element. It is also evident that the 85 resiliency of the ball may be modified or controlled by regulating the tension of the rubber strands or the degree of compression to which the sponge core or center is subjected.

I have shown and described what I be- 90 lieve to be the simplest and best exemplification of my improved ball, but the invention may have expression in somewhat modified form without departing from the spirit of the invention. 95

What I claim is:—

A ball comprising a center of compressed sponge incased in resilient rubber whereby the sponge is maintained under compression, layers of thread or yarn wound 100 under tension upon said rubber casing, the respective layers of thread or yarn being provided with a coating of cement, and an outer cover of suitable material.

ARTHUR E. MEIER.
